UNITED STATES PATENT OFFICE.

WLADYSLAUS JESCHKE, OF BROOKLYN, NEW YORK.

BOX.

SPECIFICATION forming part of Letters Patent No. 575,399, dated January 19, 1897.

Application filed March 27, 1896. Serial No. 585,047. (No model.)

To all whom it may concern:

Be it known that I, WLADYSLAUS JESCHKE, a citizen of the United States, and a resident of Brooklyn, in the county of Kings and State 5 of New York, have invented certain new and useful Improvements in Boxes or Receptacles, of which the following is a specification, reference being had to the accompanying drawings, forming a part thereof, in which similar 10 letters of reference indicate corresponding parts.

This invention relates to combination work-cases such as are usually employed by ladies for holding needles, threads, thimbles, scissors, 15 embroidery-needles, and other and similar articles, and also to holders for manicure sets, cigars, and other articles; and the object thereof is to provide an improved device 20 of this class which is simple in construction and operation, and which is also very convenient, while being comparatively inexpensive, a further object being to provide a device of this class which may be made very ornamental and which is adapted to serve as a 25 table ornament.

The invention is fully disclosed in the following specification, of which the accompanying drawings form part, in which—

Figure 1 is a perspective view of my improved work-case; Fig. 2, a plan view thereof with the cap or cover removed; Fig. 3, a perspective view of my improved device when used as a cigar-holder, and Fig. 4 a similar view showing the same adapted for use as a 35 receptacle for a manicure set.

In the practice of my invention, reference being made to Fig. 1, I provide a work-case which consists of a base A, which may be made of any desired form and which may be covered 40 with leather and ornamented to any desired extent, and at the center thereof is arranged a cushion B, which is preferably rectangular in form and also preferably square, and at each side of said cushion is hinged or 45 flexibly secured a plate D, which may be composed of pasteboard, cardboard, or any desired material, and these plates D are united by triangular corner-pieces E, which are composed of satin, silk, or similar material, and 50 the plates D are also covered on their inner sides with similar material to that which

forms the triangular corner-pieces E, and said triangular corner-pieces and the cover for the plates D may be composed of a single piece, if desired.

Part of the plates F are provided on their upper or inner surfaces with transverse strips d, which may be composed of leather, silk, satin, or any preferred material and which are provided with loops or pockets d², 60 which are adapted to serve as means for holding thimbles, scissors, crochet-needles, knives, and other articles, and one of said plates is also provided on its inner surface or face with a needle-holder G, and the cushion B at the 65 center is adapted to serve for the purpose of holding pins and other and similar articles.

The plates D may be folded together or upwardly and inwardly, and in this operation the corners E fold between the plates D, as 70 shown in Fig. 1; and I also provide a cap or cover H, which is provided with a hollow square body portion, which is adapted to inclose the plates D when folded together or to be inserted over the same, as shown in 75 Fig. 1, and may be of any desired form, but which, as shown in the drawings, is pyramidal in form and provided with a knob or ball h², which is adapted to serve as a handle.

The cap or cover H is preferably composed 80 of the same material as the base A, or said base A and said cap may be covered with the same material, and any kind of leather or silk or satin may be employed for this purpose.

In Fig. 3 I have shown my improved device 85 applied for use as a cigar-holder, and in this form of construction I substitute for the central cushion a box or receptacle B, which is designed to receive cigars, and the side plates D are adapted to be folded adjacent thereto 90 and to inclose the same, after which the cap or cover H is placed thereover, as hereinbefore described.

In Fig. 4 I have shown the same applied for use as a receptacle or holder for a manicure 95 set, in which the strips d are employed for holding various articles used for this purpose, and in this form of construction I substitute for the central cushion a puff-box, as shown at B, which is provided with a removable 100 cover b, and, as will be understood, said plates D are in this form also adapted to be folded

upwardly, so as to inclose said puff-box, in which position the cap or cover H may be placed therein.

This device is simple in construction and 5 operation and perfectly adapted to accomplish the result for which it is intended, and, as hereinbefore stated, it may be made as ornamental as desired.

My invention is not limited to the exact 10 form, construction, and arrangement of parts herein shown and described, and I reserve the right to make all such alterations therein and modifications thereof as fairly come within the scope of the invention.

15 Having fully described my invention, I claim as new and desire to secure by Letters Patent—

1. A box or receptacle of the class herein described, comprising a base, a plurality of 20 pivoted or hinged plates connected with the top thereof, and adapted to be folded together so as to inclose a space designed to receive various articles, said plates being connected by flexible corner-pieces, and a cap or cover 25 which is adapted to be placed thereover, when the plates are folded, substantially as shown and described.

2. A work-case, comprising a bottom, or base, having a central cushion formed there-

on, which is rectangular in form, side plates 30 hinged to, or flexibly connected therewith, at the base of said cushion, and adapted to be folded by flexible corner-pieces, and a removable cap or cover, which is adapted to be placed over said side plates, when so folded, 35 substantially as shown and described.

3. A work-case, comprising a bottom, or base, having a central cushion formed thereon, which is rectangular in form, side plates 40 hinged to, or flexibly connected therewith, at the base of said cushion, and adapted to be folded upwardly, said side plates being connected by flexible corner-pieces, and a removable cap or cover, which is adapted to be placed over said side plates, when so folded, 45 and each of said side plates being provided with means for holding various articles, such as scissors, thimbles, needles, and the like, substantially as shown and described.

In testimony that I claim the foregoing as 50 my invention I have signed my name, in presence of the subscribing witnesses, this 26th day of March, 1896.

WLADYSLAUS JESCHKE.
